UNITED STATES PATENT OFFICE.

FREDRIK W. DE JAHN, OF NEW YORK, N. Y.

HYDROGENIZING FATTY MATTER.

1,131,339.

Specification of Letters Patent.

Patented Mar. 9, 1915.

Application filed April 1, 1913. Serial No. 758,194.

To all whom it may concern:

Be it known that I, FREDRIK W. DE JAHN, a citizen of Norway, residing in the city of New York, borough of Manhattan, in the county of New York and State of New York, have invented certain new and useful Improvements in Hydrogenizing Fatty Matters, of which the following is a specification.

My invention relates to new and useful improvements in processes for the hydrogenizing of fatty matters containing unsaturated compounds, and the primary object of the invention is to provide an improved and more efficient process for the hydrogenizing of fatty matter, including fatty acids and their glycerids by catalysis.

Another important object of my invention is to provide for the hydrogenation of fatty matters by catalysis in a manner which will efficiently hydrogenize the fatty matter it is desired to treat, and in which the catalytic material employed will be eliminated from the product so that the method will be particularly, although not necessarily, adapted for the hydrogenation of fatty matters to be used as food.

A further object of my invention is to provide a method which will effect and maintain throughout intimate contact between the fatty matter, the added hydrogen and the catalyzer, in which the action of hydrogenation will be rapid and under complete control, and in which there will be no unnecessary loss of hydrogen.

The invention consists in the improved method for carrying the same into effect to be more fully described hereinafter, and the novelty of which will be particularly pointed out and distinctly claimed.

I have fully and clearly illustrated in the drawing forming part of this specification a preferred embodiment of an apparatus for efficiently performing my improved method.

I will now proceed to describe in detail the apparatus shown for practising the improved method.

1 designates a horizontally-disposed stationary vessel substantially cylindrical in form and of such capacity as to suit it for the treatment of the desired amount of fatty matter. This vessel is preferably covered with a suitable heat-insulating material 2, such as asbestos, and is provided at its upper side with an inlet opening 3 through which the fatty matter to be treated is introduced, said opening being provided with a suitable

detachable cover plate 4. Arranged to rotate longitudinally of the vessel 1 is a beater shaft 5 carrying suitable stirrers 6, said shaft projecting at one end beyond a head 60 of the vessel and carrying on said end a drive pulley 7, by which the shaft and stirrers are rotated. This vessel 1 is provided with heating means preferably consisting of a coil of pipe 8, arranged in the bottom 65 thereof and adapted to have steam or hot oil circulated therethrough. The vessel is also provided with a valve-controlled inlet pipe 9 for hydrogen, said pipe having connected thereto a pressure gage 10 for indicating the pressure of hydrogen supplied to, and maintained within, the vessel 1. The vessel is also provided with a suitable valve-controlled pipe 11 for supplying nitrogen, or other inert gas, to the interior of the vessel 1 for a purpose to be set forth more fully hereinafter.

12 is a pipe connected with the interior of the vessel 1 and to a suitable vacuum pump (not shown) for exhausting air from the 80 interior of the vessel 1, said pipe having connected thereto a suitable gage 13 for indicating the air pressure within said vessel 1, and being controlled by a hand valve 12^a. The vessel 1 is also provided with a valve-controlled outlet pipe 14 by means of which the contents of said vessel may be withdrawn. Opening from the bottom, preferably, of the vessel 1, is an outlet pipe 15 connected to the inlet side of a positive 90 rotary pump 16, the outlet side of which pump is connected by a pipe 17 with the upper end of a vertically-disposed reaction chamber 18, the side wall and heads of which are protected by suitable heat insulation 19, 95 In pipe 17 is a thermometer 35 for determining the temperature of the circulating emulsion. This chamber 18 is connected at its lower end with an outlet pipe 20 connected by a return pipe 21 to the inlet side of a gas 100 separator 22, which may be of any suitable construction suitable to separate gases from liquids, said separator having a valve blow-off conduit. The outlet side of the separator is connected by a valve-pipe 24 to the top of 105 the vessel 1, said pipe 24 also containing a check-valve 25 automatically closing away from the vessel 1 to prevent flow from the vessel 1 directly to the pipe 24 of gas or emulsion.

The chamber 18 is provided with a suitable pipe connection 26 to a vacuum pump,

said connection being provided with a gage 27 and controlling valves 28. The chamber 18 is also provided with a valve-controlled inlet pipe 29 for the admission of nitrogen, 5 or other inert gas, to the reaction chamber. This reaction chamber 19 has arranged therein a suitable catalyst which may consist of cobalt, palladium, nickel or any other catalyst which will bring about the desired 10 reaction. The catalyst 30 preferably consists of finely-divided nickel carried in thin layers on an inert material, such as porous burnt clay-lumps or balls, or pumice stone. The catalyst is supported upon a diaphragm 15 of perforated metal 31 located over a layer of suitable filtering material 32, the latter being supported upon the diaphragm 33 of perforated metal supported on lugs or brackets 34 at a point above the lower end 20 of the reaction chamber.

The pipe 20 is provided with a draw-off branch 20^a controlled by a valve 20^b permitting withdrawal of material in the bottom of the reaction chamber. The heads of 25 the reaction chamber are removable to permit the insertion and removal of the catalytic material, the cleansing of the interior of said chamber, or for other purposes. The heads of the chamber 1 are also removable 30 to permit of access to the interior of said vessel. All of the pipes in the apparatus for conveying the fatty matter may preferably be covered with heat insulation (not shown) with the exception, of course, 35 of the heating coil 8.

I will now proceed to describe the operation of the apparatus, above set forth, describing in detail in connection therewith my improved process.

40 The fatty matter to be treated, and preferably previously heated so as to be in a liquid state, is introduced into the vessel 1 through the opening 3, and the pump 16 is operated to draw the fatty matter from the vessel 1 and force it into the reaction chamber and the circulatory system, the operation of the pump and the supply of fatty matter being continued until the reaction chamber and the circulatory pipes are filled, 45 and the chamber 1 is substantially half filled, with the fatty matter. The circulation of heating material through the coil 8 is maintained preferably during the filling of the vessel 1 and at all times in order to 50 maintain the fatty matter in a liquid state at the proper temperature. The system having been supplied with fatty matter to be treated, as just described, the pump 16 is stopped, the closure 4 is applied to the supply opening 3, and a vacuum is applied through the pipes 12 and 26 to exhaust the air from the interior of the system, the action of the exhausting means (not shown) being continued until the gages 13 and 27 55 indicate that all the air has been exhausted

from the system. Hydrogen is then admitted to the interior of the vessel 1 through the supply pipe 9, preferably under pressure, say 100 pounds, and the stirring shaft is revolved rapidly. The stirrer operates 70 to break up the oil and form an intimate mixture of the oil and hydrogen gas. After the stirrer has been operated long enough to insure an emulsion-like condition of the fatty matter, the pump 16 is started and 75 the mixture of fatty matter and hydrogen gas will be drawn from the vessel 1 through the pipe 15 and forced through the pipe 17 into the reaction chamber, into contact with the catalyzing material therein, and the said 80 mixture brought up to a temperature of say 150°-160° C. The said mixture passes through the catalyzing material and leaves the reaction chamber through the pipe 21, flowing therethrough and through the separator 22 and pipe 24 back to the mixing chamber 1. During the passage of the mixture through the catalyzing material, the oil, hydrogen and catalyst will come into perfect contact with each other and a speedy 85 reaction will take place, resulting in effective saturation or hydrogenation of the fatty material. The circulation of the fatty matter is continued until the desired degree of hydrogenation has taken place, and the saturated matter is then withdrawn from the vessel 1 and the reaction chamber 18, after 90 the small amount of hydrogen left has been replaced, and carried off by a stream of nitrogen, or other inert gas, admitted to said 95 vessel and chamber through the pipes 11 and 29, respectively, in order to prevent explosive mixtures. During the circulation 100 of the fatty matter through the system it will be apparent that the admission of hydrogen may be kept up continuously to the vessel 1, or it may be admitted from time to time until the desired degree of saturation of the fatty material has taken place, 105 and in order to maintain a proper pressure. It will be apparent that, when the saturated 110 material leaves the reaction chamber, it will be freed of the fine particles of catalyst, having been filtered by the filtering material 32. This is important in that fatty matters 115 for use as food can be treated by this apparatus as well as fatty matters to be used for soap or other commercial purposes. The same operation takes place if a hydrogen-containing gas, such as water gas, is employed instead of hydrogen, the separator 22 serving to separate and eliminate the 120 gases from the fatty matter when it is returned to the mixing vessel from the reaction chamber. The eliminated gases escape 125 through the pipe 23. It will be understood that this pipe is closed by a suitable valve when hydrogen alone is used for saturating the fatty matter.

In carrying out the process the fatty mat- 130

ter is agitated or beaten up in the vessel 1 until it is in an emulsion-like condition consisting of minute globules confining and holding the hydrogen gas therein in a finely 5 divided condition, the purpose being to have the hydrogen gas thoroughly intermixed with the fatty matter when the latter is subjected to the catalytic action.

What I claim and desire to secure by Letters Patent of the United States is:—

1. The process of hydrogenizing fatty matter containing unsaturated compounds, which consists in first forming an intimate mixture of fatty matter with hydrogen in 15 a finely divided condition in one vessel, and subsequently subjecting the said mixture to the action of a catalytic agent in another vessel and out of contact with the matter in the first vessel.

2. The process of hydrogenizing fatty matter containing unsaturated compounds, which consists in first forming an intimate mixture of fatty matter with hydrogen in a finely divided condition in one vessel, and 25 subsequently subjecting the said mixture to the action of a catalytic agent in another vessel and circulating the fatty matter continuously through said vessels.

3. The process of hydrogenizing fatty 30 matter containing unsaturated compounds, which consists in forming an intimate mixture of fatty matter with hydrogen by agitation in one vessel, subsequently subjecting the said mixture to the action of a catalytic 35 agent in another vessel separate from the first named vessel, continuously circulating the fatty matter through said vessels and continuing the mixing the fatty matter by agitation with hydrogen in said first vessel 40 during the circulation.

4. The process of hydrogenizing fatty matter containing unsaturated compounds, which consists in first forming an intimate mixture of fatty matter with hydrogen by 45 agitation in the presence of heat in one ves-

sel, subsequently subjecting the said mixture to the action of a catalytic agent in another vessel, continuously circulating the fatty matter through said vessels, and continuing the agitation of the matter in said first vessel during the circulation. 50

5. The process of hydrogenizing fatty matter containing unsaturated compounds, which consists in introducing fatty matter into a mixing vessel and a reaction chamber 55 containing a catalyst, withdrawing air from said vessels, forming an intimate mixture by agitation of the fatty matter with hydrogen in the mixing vessel, and circulating the mixture continuously through said vessels. 60

6. The process of hydrogenizing fatty matter containing unsaturated compounds, which consists in introducing fatty matter into a mixing vessel and a reaction chamber, said chamber containing a catalyst, without drawing air from said vessel and chamber, forming an intimate mixture by agitation of the fatty matter with hydrogen in the mixing vessel, and circulating the mixture continuously through said vessels until saturation takes place, and then introducing an inert gas into said vessels. 70

7. The process of hydrogenizing fatty matter containing unsaturated compounds, which consists in first forming an intimate mixture of fatty matter with hydrogen in one vessel, subsequently subjecting the said mixture to the action of a catalytic agent in another vessel, removing the catalyst from said fatty matter, and returning the fatty matter to said first vessel, said process being conducted continuously 75 in a closed circulatory system. 80

In testimony whereof I have hereunto signed my name in the presence of two subscribers. 85
